UNITED STATES PATENT OFFICE.

CLYDE A. LAKE, OF DALLAS, TEXAS.

BRICK-MASON'S STEEL TRIG.

1,080,836.

Specification of Letters Patent.

Patented Dec. 9, 1913.

Application filed April 15, 1912. Serial No. 690,962.

To all whom it may concern:

Be it known that I, CLYDE A. LAKE, citizen of the United States, residing at Dallas, in the county of Dallas and State of Texas, 5 have invented certain new and useful Improvements in Brick-Masons' Steel Trigs, of which the following is a specification.

My invention relates to new and useful improvements in brick masons' steel trigs, 10 and its object is to provide a device especially adapted for holding a horizontal line in position upon the top of a brick wall, said line being adapted to guide the bricklayer in laying the top course of brick horizontally.

15 Heretofore, it has been the practice to support the triggling line by passing the same through several loops of string, which are retained upon the top of a wall through the weight of a brick or some other suitable 20 weight. This method of securing the line in place has proven very unsatisfactory, since the loops of string not only permit the line to sag, but also frequently become detached from the wall, and making it necessary 25 that the bricklayer secure the same again before he may proceed with his work.

It is another object of the invention to provide a triggling device that will be very simple and comparatively inexpensive and 30 that may be attached to or detached from a brick wall almost instantly.

A still further object is to provide a triggling device, the use of which will not be impeded or made impossible in the building 35 of a veneered brick wall.

With these and various other objects in view, my invention has relation to certain novel features of the construction and operation, an example of which is described in 40 the following specification, and illustrated in the accompanying drawing wherein:

Figure 1 is a perspective view, showing one end of a partially built brick wall, showing a triggling cord in proper position for 45 use by the bricklayer and showing the herein-described triggling attachment or device employed for holding the cord in position. Fig. 2 is a detail, perspective view of the triggling device, a brick wall upon which 50 the device is mounted being shown in dash lines.

Referring now more particularly to the drawing wherein like reference characters 55 designate similar parts in both the figures, the letter A denotes the loop spring formed by the middle portion of a strip of metal, which

strip has its extremities bent at right angles and folded inwardly upon themselves, as indicated by the letters B. The two parallel members B of the device are spaced a sufficient distance to permit them to grip a brick between them, after pressure has been exerted upon the loop spring A to permit 60 said members to pass down at each side of the brick. In order that the lateral edges of the device may lie in parallel planes, the portion A of the strip of which the spring is formed is reduced to a width equal to half the width of the end portions of the strip. The shoulders formed at the intersections 70 of the middle portion A of the strip with the portions C which lie between the portions A and B are designated by the letter D. The parts C lie in the same plane and are adapted to contact with the top of the 75 brick to which the triggling device is attached.

As has been previously stated, the portions B of the triggling device are of double thickness owing to the fact that these portions are folded inwardly upon themselves. The two ends of the strips are each slightly spaced from the under surface portions C of the device, thus forming two grooved channels E and F, the latter being somewhat larger than the former. When the triggling device has been clamped upon a brick, as is clearly shown in Fig. 2 of the drawing, the triggling cord G will be passed through one of the grooves E and F, and 80 will be clamped between the correlated member B and the brick upon which the device is secured. If the triggling cord is a small one, such as is ordinarily employed in working upon walls of no great length, the 85 smaller channel E will be made to receive the cord. In case a large cord is employed, the larger channel F will be made to receive the same. Obviously the triggling device is reversible, or in other words, it may 90 be so disposed upon a brick forming part of a wall that either one of the grooves E and F may be brought adjacent to the outer edge of the course of brick forming the top 95 of the wall.

In building a brick wall, it is customary to secure one extremity of the triggling cord G to a nail adjacent to one end of the wall, as indicated at H. The illustration of Fig. 1 shows how it is possible to raise the triggling cord to furnish a guide for each added 100 course of brick without necessitating an ad- 105

justment of the fixed end of the cord, which is secured at H.

It will, of course, be understood that the proportions of the above-described triggering device may be varied if necessary in a considerable number of ways, and it is also obvious that in building any wall, any number of these devices may be employed, disposed a suitable distance apart to support the triggering cord. The invention is presented as including all such modifications and changes as come within the scope of the following claims.

What I claim is:

- 15 1. A triggering device comprising a strip of metal having a resilient center portion of reduced width bent to the form of a loop, and having its end portions bent at right angles and doubled inwardly upon themselves, channels being formed between the ends of strips and the portions of the strips lying between the loop and the downturned end portions.
- 20 2. A triggering device comprising a strip of metal having a resilient central portion of reduced width bent to form a loop with

projecting ends, said ends beyond the loop being bent at right angles to form clamping jaws, the internal angle of each jaw being grooved for the purpose specified.

3. In a device of the class specified, a resilient strip comprising a reduced central portion and projecting ends, the strip being bent at its central portion to form a loop and cross adjacent to the ends of the reduced portion, the said projecting ends being bent at right angles to form clamping jaws, and the internal angle of the jaws being grooved.

4. A mason's guide line holder comprising a pair of spring-pressed right angular jaws adapted to embrace the opposite upper corners of a brick, each jaw having a line-receiving groove at the internal angle thereof.

In testimony whereof I have signed my name to this specification in the presence of two subscribing witnesses.

CLYDE A. LAKE.
